ENCLOSURE BULKHEAD

Louis F. Dietz, Englewood, N. J.

Application October 16, 1935, Serial No. 45,219

10 Claims. (Cl. 189—34)

This invention relates to paneling. For the purposes of this application I shall confine my discussion to the panels or "partitions" used in living and/or utility quarters in ships. Such discussion is illustrative only and in no way limiting, as the principles of my invention apply to other uses, as building interiors and the like.

Considering the marine partition as typical, however, it may be noted at the outset that the 10 items of camber and sheer in ship construction introduce definite factors of difficulty in the erection of such partitions on board ship.

Such partitions, commonly called enclosure bulkheads, cabin enclosures, cabin lining and 15 bulkheading, and ceiling in marine terminology, are used in constructing staterooms and other enclosures on board ship.

Heretofore these partitions have been generally constructed of wood or composition and have been 20 cut at the shipyard to suit the camber or sheer of the particular deck condition of the ship in which they are erected as stateroom or other enclosures. This introduced a factor of error which frequently necessitated re-cutting the partitions at the job.

Similarly, error was introduced in the matter of 25 having the partitions fit the desired overall sizes or shapes of the stateroom or other enclosure to be erected.

30 My invention contemplates a panel and method of erection which will avoid the necessity for cutting my bulkhead partitions or panels at the shipyard to suit the camber or sheer of the particular deck condition of the ship in which they are to be erected.

In carrying out my invention, I use top and 35 bottom channel members shaped to conform to the camber or sheer of the ship's deck and sectional panel units, there being any desired number of sections to a unit and said sections being interlockingly keyed to each other.

In erecting a stateroom or other enclosure with 40 my bulkhead panel units, where there is a camber or sheer deck condition, each panel unit is set in place and the sections thereof successively 45 driven down to the bulkhead seat of the bottom member of the stateroom or other enclosure.

This eliminates all cutting and fitting of the 50 panels to camber and sheer. It also enables the sections to be assembled in the field and arranged on the job depending on the lay-out of the particular job. The panels may be shipped as relatively narrow sections and avoids handling large panels. It also avoids cutting off the panels to 55 fit odd stateroom sizes. With my invention, only

one section of a panel needs to be cut off to fit the odd size.

In the accompanying drawings I show an embodiment of my invention which I have found highly satisfactory under actual service conditions in numerous installations.

Fig. 1 is a view of a typical installation showing an extreme camber condition of the deck.

Fig. 2 is a cross section on the line 2—2 of Fig. 3.

Fig. 3 is a fragmentary detail illustrating one 10 of the adjustable shim units which may be used in connection with my invention. This figure shows a deck condition of extreme camber or sheer.

Fig. 4 is a fragmentary detail showing the use 15 of a set screw at the top and/or bottom for holding the panel sections in their adjusted positions.

Fig. 5 is a vertical section on the line 5—5 of Fig. 1.

Fig. 6 is a fragmentary detail similar to Fig. 3 20 but showing one of the adjustable shim units as used where the deck is level or of very slight camber or sheer.

Fig. 7 is a perspective detail of one of the shim 25 units detached.

Fig. 8 is a cross section through such shim unit when assembled.

Fig. 9 is a vertical section through a bottom member in which such shim unit is used, and

Fig. 10 is a longitudinal section at right angles 30 to Fig. 8.

I have indicated at 11 the steel deck of a ship, at 12 the deck covering, at 13 a bottom member attached to the deck and providing a channel support for the bottom edges of the vertical bulkhead panel units V, at 14 a top member providing a top support for the upper edges of said panel as well as lateral supports for the ceiling panel units H, the top member being carried by the deck beams 15 from the deck above 16. The 35 vertical panel units and the ceiling panel units may or may not be duplicates. If duplicates, they are of course interchangeably useable.

Such vertical panel unit is sectional. As here 40 shown the panel units are in three sections A, B and C. These are of any desired width and may have any desired number of sections. Similarly, the sections of any panel units are thirty six inches wide, and the three sections A, B, and C thereof are each twelve inches wide.

The panel units may also be of any desired 45 thickness and any desired construction as regards fireproofing, soundproofing, or the like. As here shown the panel units are of the insulated type embodying a central core K of any suitable 50

55 type embodying a central core K of any suitable

material, as for example asbestos, and external sheathings A', A², B', B², and C', C², of steel, aluminum or the like. For convenience of shipment and assembly the asbestos or other insulated cores K may be furnished in sections. As illustrated, such cores K are furnished in three sections for each panel section (see dotted line showing of Fig. 1). Similarly the edges of the cores K may be reinforced in any desired manner as by means of the reinforced edges 17 (Fig. 5).

The vertical edges of each panel unit V are received in channelled bulkhead posts 18 (see Figs. 1 and 2) assembled with the top and bottom members. For this purpose the vertical edges of each panel unit may be and preferably are provided with channel-shaped strips 19 (Fig. 2). These lie within and are secured to the extended edges of the sheathing as at 20.

The individual sections A, B, and C constituting a panel unit are interlocked in slip joint assembly in any suitable manner. As here shown the sheathing A' at one face of the panel section A (for example) is bent laterally across the vertical edge of said section A towards the opposite sheathing member A² at the opposite face of the panel section as at 21 and then extended as at 22 in the direction of the sheathing member A². (See Fig. 2.) The sheathing A² of panel section A is extended beyond the flange 22, then bent across the vertical edge of the next panel section B as at 23 towards the sheathing B' at the opposite face of the section B, and finally bent back towards the section A, as at 24.

The sheathing B' is extended towards the panel section A and bent upon itself as at 25 and 26 to abut the portions 21 and 22 of the sheathing A'. The sheathing B² is bent as at 27 and 28 to abut the portions 23 and 24 of the sheathing A².

The abutting portions 21, 22 and 25, 26 together with the abutting portions 23, 24, and 27, 28 define an included recess which extends from top to bottom of any pair of abutting edges of adjacent panel sections. Within such recess, I insert a locking key Z. Such key is of spring material and of channel form. Its vertical edges bear against the adjacent portions 24 and 28 of the respective panel sections A and B (for example) to hold them assembled. The key fits with a drive fit and is cut to correspond to the particular deck condition of camber or sheer.

In erecting the vertical bulkhead panel units on ships where there is a camber or sheer condition, each panel unit is fitted into place between its supporting bulkhead posts 18. The several sections A, B, and C etc. of such unit are then successively driven down to their seats on the bottom member 13. This eliminates all cutting and fitting to camber or sheer.

After the several panel units have been fitted to the prevailing deck condition of camber or sheer, set screws 29 and 30 or their equivalents may be inserted through the top and bottom bulkhead seats to hold the panel sections in their adjusted positions. If the decks are level or of very slight camber or sheer, then the abutting portions 21, 25, and 23, 27, respectively may be spot welded rather than adjustably secured to each other as by means of the set screws 28 and 30.

Under some conditions it is desirable to provide adjustable shim units at the bottom edges of the panel units. Where this is done, it is preferable to provide a shim unit for each panel section. These may be adjusted to suit the particular condition of camber or sheer of the deck.

Fig. 3 shows an adjustable shim unit supporting the bottom edge of a panel section on a deck having an extreme condition of camber, as in Fig. 1. Fig. 6 shows such adjustable shim unit when used with a relatively level deck or one having a very slight camber or sheer.

Referring to these figures and to Figs. 7 to 10 inclusive which illustrate the construction of the adjustable shim units and their manner of assembly within the bottom member 13, it will be noted that each adjustable shim unit comprises a pair of superposed wedge-shaped shims 31 and 32.

The top shim member 31 is formed with in-turned flanges 33 at its top longitudinal edges. These support the bottom edge of the panel section, as best shown in Fig. 9. The lower shim member 32 has its bottom longitudinal edges in-turned as at 34 to rest upon a part of the bottom member 13.

The inclined faces of the shims 31 and 32 slidably engage each other in the manner of a wedge, the upper face of the bottom shim 32 being longitudinally slotted substantially from end to end thereof as indicated at 35, and the bottom face of the upper shim 31 being perforated as at 36 to receive a set screw or its equivalent 37 disposed in the slot 35 for permitting and holding the sliding adjustment of the members 31 and 32 relative to each other.

Various other modifications in construction and arrangement may obviously be resorted to within the spirit and scope of my invention, as defined by the appended claims.

What I therefore claim and desire to secure by Letters Patent is:—

1. Enclosure bulkheads comprising top and bottom members and vertical bulkhead posts and panel units assembled therewith, each panel unit comprising a plurality of sections, and said sections comprising each a pair of spaced sheathing members, opposite sheathing members of adjacent sections overlapping each other and each having a portion extending towards the other to form an enclosed space, and locking keys within said spaces and permissive of relative up and down adjustment of the individual sections of a panel unit relative to one another to suit the camber or sheer of a particular deck condition, said keys being driven and frictionally engaging the walls of the enclosed spaces.

2. The combination of claim 1 wherein supporting devices are assembled with the bottom members and adjustably space the bottom edges of the panel sections from the bottom member.

3. The combination of claim 1 wherein wedge-shaped shims are assembled with the bottom members and adjustably space the bottom edges of the panel sections from the bottom member.

4. A slip joint for interlocking the adjacent sections of a sectional panel unit to enable said sections to be fitted to the camber or sheer of a deck when used as an enclosure bulkhead, said sections comprising each a pair of spaced sheathing members, each sheathing member having a portion extended towards the opposite sheathing member, and said extensions defining with each other and with the similarly extending portions of the sheathing members of an adjacent panel section an enclosed space and a spring locking key within said space, said key being driven and frictionally engaging the walls of the enclosed space.

5. The combination of claim 4 wherein set screws or their equivalents are engaged with the

abutting edges of adjacent sections of a panel unit for holding said sections in their adjusted positions.

6. The combination of claim 4 wherein shim units are assembled with the panel units, each comprising a pair of adjustable shim members having mutually contacting inclined faces, the face of one shim member being longitudinally slotted to permit the cooperating shim member 10 to be slid therealong, there being means disposed in said slot and engaged with the cooperating shim member for holding the adjustment of said shim members relative to one another.

15 7. A panel unit comprising a plurality of sections, said sections comprising each a pair of spaced sheathing members, opposite sheathing members of adjacent sections overlapping each other and each having a portion extending towards one another to form an enclosed space, and a locking key within said space, said key being driven and frictionally engaging the walls of the enclosed space.

8. A panel unit comprising a plurality of sections, said sections comprising each a pair of spaced sheathing members, each sheathing member having a portion extended towards the opposite sheathing member, and said extensions defining with each other and with the similarly 20 extending portions of the sheathing members of an adjacent panel section an enclosed space, and a spring locking key within said space, said key being driven and frictionally engaging the walls of the enclosed space.

25 9. A panel unit comprising a plurality of sec-

tions, said sections comprising each a pair of spaced sheathing members, the sheathing members of two adjacent sections at one side of the panel unit having transversely bent portions disposed substantially in abutment with each other, 5 the sheathing members of said adjacent sections at the opposite side of the panel unit having transversely bent portions disposed substantially in abutment with each other and spaced from said first-named bent portions and defining 10 therewith an included recess, and a locking key in said recess, said key being driven and frictionally engaging the walls of the included recess.

10. A panel structure comprising a pair of panel sections disposed in edge to edge relationship, sheathing members at the sides of each panel, one sheathing member of each panel section being directed across the edge of the panel section to the other sheathing member, the latter sheathing member of each panel section being 15 extended outwardly beyond the edge of the panel section, thence across the edge of the panel section in spaced relationship thereto and thence inwardly toward the edge of the first panel section, the extended portions of the sheathing 20 members of the respective panel sections being disposed at opposite sides of the panel structure and in overlapping interfitting relationship, and a key between the extended and the inwardly directed portions of the sheathing members of 25 the respective panel sections locking the panel sections against relative lateral movement and also against separation by movement of either section in its plane.
